US0D1013376S

(12) **United States Design Patent** (10) **Patent No.:** **US D1,013,376 S**
(45) **Date of Patent:** **** Feb. 6, 2024**

(54) **LUGGAGE**

(71) Applicant: **JRSK, Inc.**, New York, NY (US)

(72) Inventors: **Stephanie Korey**, New York, NY (US);
Jennifer Rubio, New York, NY (US);
Bret Recor, San Francisco, CA (US);
Seth Murray, San Francisco, CA (US);
Charles Weber, San Francisco, CA (US);
Ahyoung Park, San Francisco, CA (US)

(73) Assignee: **JRSK, Inc.**, New York, NY (US)

(**) Term: **15 Years**

(21) Appl. No.: **29/854,153**

(22) Filed: **Sep. 22, 2022**

Related U.S. Application Data

(63) Continuation of application No. 29/726,108, filed on Feb. 28, 2020, now Pat. No. Des. 966,704, which is a continuation of application No. 29/609,840, filed on Jul. 6, 2017, now Pat. No. Des. 880,156, which is a continuation of application No. 14/935,335, filed on Nov. 6, 2015, now Pat. No. 10,219,599.

(57) **CLAIM**

The ornamental design for luggage, as shown and described.

DESCRIPTION

FIG. 1 is a front perspective view of the luggage showing our new, original and ornamental design embodied therein, in accordance with the present invention;
FIG. 2 is a rear perspective view thereof;
FIG. 3 is a front elevational view thereof;
FIG. 4 is a rear elevational view thereof;
FIG. 5 is a top view thereof;
FIG. 6 is a bottom view thereof;
FIG. 7 is a first elevational side view thereof; and,
FIG. 8 is a second elevational side view thereof.
Any dash-dash broken lines in the drawings, including any dash-dash broken line over a claimed surface, represent unclaimed portions of the luggage and form no part of the claimed design.

1 Claim, 8 Drawing Sheets
